(57) **CLAIM**

The ornamental design for a dispenser roll, as shown and described.

DESCRIPTION

This application claims priority to U.S. Design patent application Ser. No. 29/189,923, filed Sep. 12, 2003, U.S. Design patent application Ser. No. 29/189,924 filed Sep. 12, 2003 and U.S. Design patent application Ser. No. 29/189,949, filed Sep. 12, 2003 all entitled “Dispenser Roll.”

FIG. 1 is a top, front, and left side perspective view of a dispenser roll showing our new design;

FIG. 2 is a front elevational view thereof;

FIG. 3 is a rear elevational view thereof;

FIG. 4 is a right end elevational view thereof;

FIG. 5 is a left end elevational view thereof;

FIG. 6 is a top, front, and left side perspective view of the left end portion of the roll thereof;

FIG. 7 is a front elevational view of the right end portion of the roll thereof; and,

FIG. 8 is a rear elevational view of the right end portion of the roll thereof.

The broken-line disclosure in the views is for illustrative purposes only and forms no part of the claimed design.
